(57) **CLAIM**

The ornamental design for a watercraft pet seat as shown and described.

DESCRIPTION

FIG. 1 is an upper perspective view of the watercraft pet seat of the instant invention;

FIG. 2 is a front end view thereof;

FIG. 3 is a rear end view thereof;

FIG. 4 is a left side view thereof;

FIG. 5 is a right side view thereof;

FIG. 6 is a top view thereof;

FIG. 7 is a bottom view thereof; and,

FIG. 8 is a perspective view thereof.

The broken lines represent environmental subject matter and form no part of the claimed design.
